UNITED STATES PATENT OFFICE.

CHARLES A. BLUHM, OF MICHIGAN CITY, INDIANA.

INCANDESCENT GAS-BURNER.

SPECIFICATION forming part of Letters Patent No. 694,824, dated March 4, 1902.

Application filed June 1, 1901. Serial No. 62,761. (No model.)

To all whom it may concern:

Be it known that I, CHARLES A. BLUHM, a citizen of the United States of America, residing at Michigan City, in the county of La-
5 porte and State of Indiana, have invented certain new and useful Improvements in Incandescent Gas-Burners, of which the following is a specification.

My invention relates to an improvement in incandescent gas-burners, an object being to provide a burner of the Welsbach type and to provide improved means for carrying the gas commingled with air and distributing it by a circular discharge from the inlets to the top
10 or highest point of the mantle, and in connection with these features to provide for a proper circulation and supply of air, whereby the light continues without variation as long as the gas is turned on. Failure to recognize this requirement has resulted in a lack of success in the construction in many, if not all, of the incandescent gas-burners at present on the market. The reason for this is that the gas in passing through the small openings in the
15 disk generally used and on the market causes the passages to become clogged by corrosion of the gas after being used a while, and the result is a variation in the openings of the disk. This variation in the size of openings creates
20 a heavier discharge of gas through the larger openings located, probably, at one side, and thereby passing the flame to one side of the mantle, and with the same regulation of air the flame and heat are carried to one side,
25 causing the mantle to burn out and give only a partial and imperfect flame on the opposite side, producing a gloomy light and at times only a partial lighting of the mantle.

It is an object of my present invention to
30 overcome this objection by the use and introduction of a valve and a valve-seat or opening in this disk, said valve being cone-shaped and adapted to be screwed up or down to regulate the size of the opening and the amount
35 of discharge of the gas, at the same time spreading the gas as it discharges through the orifice. My burner is so constructed that should the cone or valve become clogged by corrosion it can be easily removed and cleaned
40 and replaced again for use.

A still further object of my invention is to

prevent the momentary explosion resulting from the lighting of the gas, which is the case with all of the burners now on the market, and which explosion by combustion in lighting the gas weakens and finally destroys the mantle, and these results are attained in my present invention by a proper regulation of air-supply, whereby the full force of the air in the air-chamber is maintained and the variation in supply of air is not permitted to change the spread of gas issuing through the orifice.

With the foregoing and other objects in view my present invention consists in certain novel features of construction and combinations of parts, which will be hereinafter described and particularly pointed out in the claims.

In the accompanying drawings, Figure 1 is a vertical section taken centrally through my improved burner. Fig. 2 is an enlarged detail in section, showing the valve, valve-seat, and connected parts. Fig. 3 is a horizontal section on the line $\alpha\alpha$ of Fig. 1, and Figs. 4 and 5 are details.

The pillar of the burner comprises a threaded thimble 1, adapted to screw on the gas pipe or fixture, and a tube 2, secured thereto. The two parts may be connected together
50 in any approved manner; but, preferably, they are screwed together as shown at the nipple 3. The tube is provided with a circumferential rib 4, which has a double function, one of which is to confine the air-regulating sleeve 55 5, which controls the air-openings 6 between it and the thimble 1, and its other function is to provide a seat or bearing for the air-chamber gallery and mixing-chamber to rest
60 and turn upon.

Proceeding for the present to a brief description of the last-named parts, the numeral 7 indicates the air-chamber. This chamber is stamped or otherwise made from thin sheet metal, preferably in about the form indicated
65 in the drawings, it being provided with openings in the bottom, as indicated at 8, for the entrance of air thereinto. As this chamber supplies air to the orifices 6, where it commingles with the gas-supply, it will be termed
70 an "air-mixing" chamber. From the upper end of the air-mixing chamber a tube 9 ex-

tends, and on the upper end of the latter the mixing-chamber 10 is mounted, the tube 9, in other words, thus connecting the air-chamber and mixing-chamber and forming a means of 5 communication between the two. Tube 9 is of a size to just fit the upper end of tube 2, and to insure adequate frictional contact therewith the latter tube is split at the upper end, as indicated at 11, to permit suitable 10 expansion of the upper end of tube 2 to insure this proper frictional engagement of these parts to cause the tube 9 to remain in position when turned or rotated on the pillar.

The numeral 12 indicates the usual gallery, 15 which latter is connected, as indicated, at the top and bottom with parts of the burner, at the top by means of a spider 13 with the mixing-chamber for convenience and the bottom with the top of the air-chamber by means of 20 the cage 14, in which latter openings 15 are formed for the admission of air and the insertion of a match or taper for lighting the gas. Of course the burner could be lighted from above the mantle, if desired. The mantle 25 is indicated at 16, it being held in position on the combustion-chamber by means of the cap 17 and the supporting-arm 18, as is customary. The chimney 19 is supported on the gallery in the usual manner, and arms 20 are 30 provided for the support of a shade outside of the chimney.

My improved means for regulating the gas-supply will now be described.

In the bore of the thimble 1 a plug 21 is 35 fitted, it being held by frictional contact or otherwise, as the case may be. A shoulder 22 limits the inward movement of this plug, whereby gas-chamber 23 intervenes between its inner end and the diaphragm 24, formed 40 across the inner or upper end of the thimble. Gas-ducts 25 extend through this plug for supplying the gas-chamber 23 as fast as the gas is required or consumed. From the center of the plug 21 a screw-threaded stem 26 45 extends upwardly through an orifice 27 in the diaphragm 24, the edges of which orifice 27 are beveled or inclined, as indicated at 28, to form a valve-seat.

The numeral 29 indicates a conical valve, 50 which has a screw-threaded bore 30, adapted to turn or screw upon the threaded stem 26, whereby the conical valve is raised or lowered and the tapering lower end 31 of the valve made to open or close the orifice 27, thus regulating the influx of gas according to the 55 amount of consumption required and insuring its entrance in the form of an annular head, which is spread outwardly by the lower taper of the valve preparatory to intermin- 60 gling with the air-supply in the air-chamber 7, and which air enters through the openings 66 into the pillar to commingle with the gas and supply oxygen to support combustion, its supply being regulated by the air-regulat- 65 ing sleeve 5, previously alluded to. From the upper end of the valve 29 a rod 32 extends.

The upper end of this rod is angular in cross-section and has a loose sliding connection through a hole 33 of corresponding shape and made to receive it in the perforated disk 34, 70 secured at the lower end of the mixing-chamber. This disk has the function of a wrench in a sense, or, in other words, it connects the valve 29 with the upper parts of the burner, including the air-chamber, mixing-chamber, 75 connecting-tube, and gallery, in such a manner that when these parts, all of which rest and are capable of turning on the circumferential rib or bearing 4, are turned or rotated the valve 29 is raised or lowered, as the case 80 may be, to regulate the supply of gas to the burner or to shut it off altogether. From the foregoing the object of the angular formation of the upper end of the rod 32 and the corresponding slot 33 in the disk 34 will be readily understood, as the upper portions of the burner, including the air-chamber, mixing-chamber, and gallery, merely rotate upon the rib or seat 4, whereas the valve 29 not only 85 turns, but as it turns is moved endwise up or down as the parts are turned to the right or left. The rotation of these parts is limited by the stop 37 on the thimble 1 and the spring-handle 38, which controls the air-regulating sleeve 5, the spring 38 resting and sliding in 90 a notch 39, provided for it in the base of the air-mixing chamber, this spring 38 being in position at all times, whether the sleeve 5 be raised to close or partly close the openings 66 or lowered to strike the stop when the rotary 100 parts have been turned far enough and prevent further movement beyond that point and, in consequence, further movement of the conical valve. In other words, the rotary parts of the burner are limited by the stop 105 37 and the spring 38 to a turn slightly less than a complete rotation, such adjustment of the valve being sufficient to meet the requirements of the burner.

From the foregoing it will be seen that all 110 the foregoing objects of my invention are accomplished and fulfilled by the construction described, and, furthermore, it will be understood that the parts may be separated with the utmost convenience whenever occasion 115 may require. The upper portion of the burner carrying the mantle may be lifted from the pillar without removing the pillar from the gas pipe or fixture, or the entire burner may be removed from the pipe or fixture by first unscrewing the thimble 1 therefrom, after which the pillar is removed from the other parts by pulling it therefrom. Then access may be had to the valve 29 by unscrewing the thimble 1 and tube 2, and the 120 valve 29 may be removed by unscrewing it from the stem 26, and the plug 21 may be easily forced out of the thimble. In this way all parts which might require cleaning or renewal are made easily accessible and can be 125 removed, repaired, or renewed at pleasure. 130 It is evident that slight changes might be

made in the form and arrangement of the several parts described without departing from the spirit and scope of my invention, and hence I do not wish to limit myself to the exact construction herein set forth; but,

Having thus fully described my invention, what I claim as new, and desire to secure by Letters Patent, is—

1. A gas-burner comprising a fixed and a rotatable portion, the fixed portion comprising a slotted tube and a threaded thimble adapted to be secured to a gas pipe or fixture and having a gas-orifice therein, a valve constructed and adapted to be controlled by the rotatable part of the burner for regulating the size of said orifice, and an air-regulating sleeve mounted on the tube for opening and closing the slots in the tube for regulating the supply of air to the burner.

2. A gas-burner comprising a fixed and a rotatable portion, the fixed portion adapted to be secured to a gas pipe or fixture and having a gas-orifice therein, a valve constructed and adapted to be controlled by the rotatable part of the burner for regulating the size of said orifice, means for regulating the supply of air to the burner and stop mechanism with which the handle of said air-regulating means co-operates to limit the movement of the rotatable parts of the burner.

3. A gas-burner comprising a fixed and a rotatable portion, the fixed portion having a gas-orifice formed therein and a valve controlled by the rotatable part of the burner and with which valve said rotatable part has a sliding connection, said valve constructed and adapted to regulate the discharge of gas through the orifice.

4. In a gas-burner, the combination with a pillar having a diaphragm therein, said diaphragm provided with a gas-orifice, and a suitably-supported threaded stem extending centrally through said orifice, of a valve screwed on the threaded stem and means for turning the valve to close or regulate the size of the orifice.

5. In a gas-burner, the combination with a pillar having a diaphragm therein, said diaphragm provided with a gas-orifice, and a suitably-supported threaded stem extending centrally through the orifice, of a conical valve screwed on the threaded stem, the conical exterior of the valve constructed and adapted to close or regulate the size of the gas-orifice in the diaphragm and also to spread the gas issuing therethrough.

6. In a gas-burner, the combination with a pillar constructed and adapted to screw on a gas pipe or fixture, a diaphragm extending across the interior of the pillar and having a gas-orifice formed therein, and a plug fitting the bore of the pillar, said plug having a gas-duct therein, a gas-chamber intervening between the inner end of the plug and the diaphragm, and the plug having a screw-threaded stem thereon which extends centrally through the gas-orifice, of a valve adapted to

screw up and down on the threaded stem for closing or regulating the size of the gas-orifice.

7. In a gas-burner, the combination with a pillar constructed and adapted to screw on a gas pipe or fixture, a diaphragm extending across the interior of the pillar and having a gas-orifice formed therein, and a plug fitting the bore of the pillar, said plug having a gas-duct therein, a gas-chamber intervening between the inner end of the plug and the diaphragm, and the plug having a screw-threaded stem thereon which extends centrally through the gas-orifice, of a valve having a conical lower end and a threaded bore adapted to screw on the stem, and means for turning the valve whereby to close or regulate the size of the gas-orifice, the conical end of the valve serving as a spreader for the gas issuing through the orifice.

8. In a gas-burner, the combination with a pillar having a gas-orifice formed therein, of a valve for closing or regulating the size of said orifice, a rotatable portion of the burner, a disk therein having an angular opening and a rod extending from the valve loosely through said opening whereby the valve is turned with the rotation of the rotatable portion of the burner.

9. In a burner, the combination with a pillar composed of a tube and thimble removably secured together, the pillar having a diaphragm therein, said diaphragm provided with a gas-orifice, a plug fitted to the bore of the thimble and provided with a gas-duct, and a screw-threaded stem extending from the plug centrally through the gas-orifice in the diaphragm, of a valve which screws on said stem for closing the orifice or regulating the size thereof.

10. In a burner, the combination with a pillar composed of a tube and thimble removably secured together, the pillar having a diaphragm therein, said diaphragm provided with a gas-orifice, a plug fitted to the bore of the thimble and provided with a gas-duct, and a screw-threaded stem extending from the plug centrally through the gas-orifice in the diaphragm, of a valve which screws on said stem for closing the orifice or regulating the size thereof, the pillar having air-openings therein, an air-regulating sleeve mounted to slide on the pillar and regulate the size of these openings and means for holding it in position.

11. The combination with a pillar comprising a tube and thimble, the tube having a circumferential rib formed thereon and provided with air-openings below said rib, of an air-regulating sleeve mounted loosely on the pillar and confined in its movements between the rib and a projection on the thimble and a spring-handle for raising and lowering said sleeve.

12. The combination with a pillar comprising a tube and thimble, the tube having a circumferential rib formed thereon and provided

- with air-openings below said rib, of an air-regulating sleeve mounted loosely on the pillar and confined in its movements between the rib and a projection on the thimble, a 5 spring-handle for raising and lowering said sleeve and a stop on the pillar which the spring is adapted to strike to confine the rotary movements of the burner.
13. The combination with a pillar having 10 a stop thereon and provided with air-openings and a gas-orifice, a sleeve for controlling the air-openings, a spring-handle depending therefrom, an air-mixing chamber mounted to turn on the pillar and provided with a notch 15 to receive the spring-handle on the sleeve, of a valve constructed and adapted to turn with the air-mixing chamber for controlling the size of the gas-orifice in the pillar or for closing the latter.
14. The combination with a pillar provided 20 with air-openings and a diaphragm having a gas-orifice formed therein, and a valve for closing or regulating the size of said orifice of a connected air-mixing chamber, mixing- 25 chamber and gallery having rotatable connection with the pillar and sliding connection

with the valve whereby the latter is operated with the rotations of the combined air-mixing chamber, mixing-chamber and gallery.

15. The combination with a pillar provided 30 with air-openings and a diaphragm having a gas-orifice formed therein, and a valve for closing or regulating the size of said orifice, of an air-mixing chamber, a mixing-chamber, a tube connecting said chambers together, 35 fitting the pillar and rotatably connected therewith, a gallery connected with the tube, a disk extending across the mixing-chamber and provided with a centrally-located angular opening and a rod extending from the 40 valve and provided with an angular portion which has sliding connection with the angular opening in the disk whereby when the rotatable parts are turned the valve is raised or lowered. 45

In testimony whereof I have signed my name to this specification in the presence of two subscribing witnesses.

CHARLES A. BLUHM.
